[57] CLAIM

The ornamental design for a combined sign and canopy roof structure for a fast service restaurant building, as shown and described.

DESCRIPTION

FIG. 1 is an upper front corner perspective view of a combined sign and canopy roof structure for a fast service restaurant building;

FIG. 2 is a top plan view thereof;

FIG. 3 is a front elevational view thereof;

FIG. 4 is a left side elevational view thereof, the right side being a mirror image of the left side;

The broken line showing of indicia in FIGS. 1-4 and of building wall structure in FIGS. 1, 3, and 4 is for purposes of illustration only and to show the environment of the invention.

FIG. 1

FIG. 2

FIG. 3

FIG. 4
